UNITED STATES PATENT OFFICE

JOHN MATTHEW MILLER, OF NEW BRUNSWICK, NEW JERSEY, ASSIGNOR TO CHARLES SHEPARD, OF ROCHESTER, NEW YORK

HULL

Application filed November 7, 1924. Serial No. 748,392.

The invention relates to improvements in hulls designed especially for amphibians or flying boats, in which the landing gear wheels are mounted in connection with an inverted V, bottom hull or pontoon, and the objects of the improvement are: first, to provide an improved location and action for the landing gear and wheels; second, to secure a hull design for greater lateral stability; and 1) third, to give greater clearance between the hull and the ground. This last feature is very important and impossible to secure by any other known design.

One form of the invention is illustrated 15 in the accompanying drawing, in which:

Figure 1 is a vertical sectional view through parts of the apparatus, showing the wheels in their lowered position ready for landing on or taking off from the ground, the 20 section being taken approximately on the line 1-1 of Fig. 2;

Fig. 2 is a diagrammatic plan of the hull and lateral fins showing the location of the wheels, the wings and other parts of the aero- 25 plane being omitted for the sake of clear- ness;

Fig. 3 is a side elevation of the aeroplane, illustrating the wheels in their lowered position for use in landing on or taking off 30 from land;

Fig. 4 is a view similar to Fig. 3, with parts omitted, illustrating the wheels retracted for landing on or taking off from water; and

Fig. 5 is an elevation of the retracting 35 mechanism comprising a wheel supporting member and a guideway in which it moves, showing details thereof.

Referring now to the drawings, which 40 illustrate a preferred embodiment of the invention, the section 6 constitutes the main body of the hull. The two sections 7, 7 constitute side fins to aid in securing lateral stability. The wheels 8, 8 along with the tail-skid 9, form the landing gear for use in 45 landing upon or taking off from the ground. The angle formed by the inverted V bottom is shown at 10 in Fig. 1, which figure also illustrates the ample ground clearance secured by this design.

50 The wheels 8 are mounted so that they

may be retracted or moved upwardly from the position shown in Figs. 1 and 3 to that illustrated in Fig. 4. In this latter or retracted position, each wheel may be received partially within a recess or housing in a 55 lateral fin 7, as is plainly shown in Fig. 4. One side of each of these housings may be formed by the side of the main hull section 6, as shown in Figs. 1 and 2, while the other side thereof is indicated by the liens 18 in 60 these two figures.

Referring now to Fig. 5, which shows in detail the construction of the retracting mechanism, the guide 11, 11 controls the action of the slide 12, on which the wheel 8 is 65 mounted. The locking bolts 13, 13 hold the slide in a lowered position, and they in turn are held by springs 14. The numerals 8 and 15, indicate respectively the wheels and shock absorbers. A pull or tension upon the cable 16, which leads from a winding drum over suitable sheaves to the wheel retracting mechanism, first withdraws the bolts 13, 13 from locked position, and continued pull on the cable raises the entire slide (12) 70 vertically in the guide (11). The slide returns to the lower position by gravity when tension is released from the cable 16, and is automatically locked in position by the spring 75 pressed bolts. The raising and lowering 80 could also be accomplished by a stiff bar or rod joined to the bolts by bell cranks at the lower end and arrange the bell-cranks so that the first upward motion of the rod retracts the bolts and continued motion lifts 85 the wheel. The rod could be operated by rack and pinion, or a screw thread. It will also be noticed that the guide and slide are used for two purposes, namely; first, to raise and lower the wheel, and second, to take the 90 motion permitted by the shock absorbers 15. In this way, the usually complicated mechanism used for raising and lowering these parts is done away with, and a simple and reliable mechanism is provided.

95 It is to be especially noted that I prefer to place the wheels of my device at the sides of the hull, these being at the same time, the lowest points of the structure. Heretofore amphibians have been made with the hulls of 100

either V shape or flat on the bottom. When the bottom of V shape is used, the wheels must be placed at a considerable distance below the sides of the hull, so that the lowest part of the hull, at the center, will have ample clearance above the ground. This arrangement is weak and unstable due to the difficulty of properly bracing the wheels when placed at such a great distance from the hull, and is expensive and heavy on account of the many parts necessary. When the bottom of the hull is flat, the result is improved but the wheels must still be placed at quite a distance below the hull to allow sufficient clearance in the center to avoid obstructions, such as stumps in the landing field. Also, the desirable V bottom design is lost. With my arrangement on the other hand, the wheels are placed close to the hull, thus allowing the use of short, easily braced, light and inexpensive connections between the wheels and the hull. At the same time, the bottom of the hull slopes upward from the wheels toward the centre, thus furnishing ample clearance for the machine to pass over all usual obstructions, and it will be noticed that the skid gives ample protection for the rear end of the hull and is especially designed to meet such obstructions, while the rest of the hull cannot be so designed, as the weight of the material would be prohibitive.

In closing, I desire to emphasize four requirements of flying boat and amphibian design that have been met and improved on; First, a hull of far greater lateral stability has been developed as may be seen, by the fact that the displacement increases as the hull is tipped. In the usual type of hull the displacement decreases as the hull is tipped. Second, ample clearance has been secured between the bottom of the hull and the ground. This important feature may not impress the layman, but it is an Army requirement that has never been satisfactorily met in previous amphibian design. Third, to locate wheels in such a position that they will in no way interfere with the water. In V or flat bottom design the water is thrown out from the center of the hull and in order to get the wheels entirely clear of this disturbed water, it is necessary to swing them well above the water line and to such a position that they will not catch or deflect the spray. On the other hand, with the inverted V bottom hull it has been proved in actual practice and in model basin tests conducted by the Navy Department, that the water is not thrown out by the hull, but is thrown in towards the center. So it will be seen that the side of the boat will be left free from water and that a very desirable location for the wheels have been secured. This fact was very clearly brought out in recent tests. Fourth, to secure a hull that will enter and leave the water easily, especially a hull that will land on the water smoothly without

pounding. The V bottom type does not fulfill all the desired results as it throws much water to the side and nautically speaking "is very wet." The flat bottom has the same fault and furthermore is obsolete as it pounds so hard on landing in the water, that only an expert can successfully get one on the water from a flying position. However, the inverted V bottom fully overcomes both these objections, as has been proved by tests.

Thus it will be seen that that I have provided a novel and advantageous combination of wheels and hull in an amphibian, resulting in a lighter, stronger, safer, and cheaper construction; having fewer parts and being therefore easier to inspect and keep in proper condition.

I claim:

1. In a device of the character described, the combination with an aeroplane supporting surface, of a hull, lateral fins at the sides of said hull, and wheels for supporting said device on land, said wheels being retractable from their supporting position to a position within housings formed in said fins, one side of said housings being substantially identical with a portion of the side of said hull.

2. In a device of the character described, a hull having a substantially vertical side, a lateral fin attached to said side, and a recess in said fin, one side of said recess being substantially coincident with the said side of the hull, said recess adapted to have a wheel retracted thereinto.

3. In a device of the character described, a hull, a lateral fin on said hull, and a guideway along the side of said hull and extending into said fin.

4. The combination with a guideway, of a member slidably mounted therein, means for retaining said member in fixed position relative to said guideway, a second member slidably mounted in the guideway, a resilient connection between the first member and the second member so that said second member is resiliently restrained against movement in said guideway when said first member is fixed relative thereto, an axle mounted in cantilever fashion on said second member and supported entirely thereby, and a wheel mounted upon said axle.

5. The combination with a guideway, of a member slidably mounted therein, means for retaining said member in fixed position relative to said guideway, a second member slidably mounted in the guideway, a resilient connection between said first member and said second member, an axle fixed to said second member at a point horizontally offset from said resilient connection, and a wheel mounted on said axle, said second member having a diagonal strut extending from said axle to said resilient connection so as to transfer stress from the axle to the resilient connection.

6. An amphibious aeroplane comprising, in combination, wing surfaces for supporting said aeroplane in flight, a hull member for supporting said aeroplane on water, a fin member joined to and extending laterally from said hull member, a cavity in one of said members adjacent the junction between said hull member and said fin member, a wheel for supporting said aeroplane on land, and means for shifting said wheel to an ineffective position substantially within said cavity.

JOHN M. MILLER.
